UNITED STATES PATENT OFFICE.

JAMES FRANCIS BARTLETT, OF CLEVELAND, OHIO, ASSIGNOR OF ONE-HALF
TO J. DWIGHT PALMER, OF SAME PLACE.

FASTENING DEVICE FOR SHIPPING-CASES.

SPECIFICATION forming part of Letters Patent No. 355,497, dated January 4, 1887.

Application filed September 23, 1885. Serial No. 177,921. (No model.)

To all whom it may concern:

Be it known that I, JAMES FRANCIS BARTLETT, a citizen of the United States, residing at Cleveland, in the county of Cuyahoga and State 5 of Ohio, have invented certain new and useful Improvements in Fastening Devices for Shipping - Cases; and I do declare the following to be a full, clear, and exact description of the invention, such as will enable others 10 skilled in the art to which it appertains to make and use the same, reference being had to the accompanying drawings, and to letters or figures of reference marked thereon, which form a part of this specification.

15 This invention relates to shipping-cases and fastening devices therefor.

The object is to produce an egg-carrier which can easily be opened and closed; which is capable of safe and firm closure in transportation, and will be strong at the fastenings; in which the retaining parts will be held and protected by portions of the cover, which portions will serve also as means whereby any 20 loosening of the retaining parts may readily be cured, and in which the cover may be placed in position without particular attention.

It is not broadly new to construct a shipping-case with a removable cover provided 30 with a sliding bolt at one end and a catch at the other, the bolt to take into a slot in one end of the box portion of the case and the catch to take into a slot in the other end thereof; but in all shipping-cases of which I 35 am aware the construction and attachment of the fastenings do not appear sufficiently simple, the retaining devices do not seem to be properly protected, when they become loose are not readily tightened, and the ends of the 40 cover are not interchangeable.

The present invention consists in a fastening for a shipping - case of the kind in which the cover is provided at one end with a bolt and at the other with a catch, bolt and catch 45 to take into suitable slots in the ends of the box portion of the case, in which shipping-case the catch, and the housing of the bolt also, if desired, are held in place and protected by cleats upon the under side of the cover, the 50 cleats being so attached to the cover that if the

catch or the bolt come loose it may be tightened by simply striking upon its cleat.

Furthermore, the invention consists in a shipping-case the sides of the box portion of which are provided with slots, and with 55 grooves over the slots and extending beyond them laterally, such grooves being filled by strips of wood, to serve as strengthening-strips.

Finally, the invention consists in a shipping-case having a removable cover provided with 60 a bolt at one end and a catch at the other, and with suitable slots, the bolt and catch being of substantially the same form, so that either one or the other may be used as a bolt or a catch, and either one, when in position, be inserted 65 into either slot, whereby the cover is made interchangeable end for end.

In the accompanying drawings, forming part of this specification, and in which like letters of reference designate corresponding parts, 70 Figure 1 is a vertical longitudinal section of a shipping-case for carrying eggs, showing the body or box portion divided by a partition into two parts for the reception of trays placed one upon another and separated by sheets of 75 paper, showing the ends of the box, provided with holes for convenience of carrying, projecting a short distance above the sides of the case, the projecting portions grooved and the grooves provided with strengthening-strips; 80 also showing a removable cover having at one end a sliding bolt and at the other a catch, both the sliding bolt and the catch being provided with a spur or small projection, that on the sliding bolt forming a handle to move it 85 back and forth, and that on the catch serving to stick it to the cover; also showing a sheet-metal plate that houses the bolt and retains it by friction from unnecessary sliding; also showing a cleat protecting the sliding bolt and 90

preserving and increasing the frictional contact between the same and metal plate, and also showing the catch protected and held in place by a cleat. Fig. 2 is an end elevation with a portion broken away to show the cleat; 95 also showing a slot which is entered by bolt or catch; also holes to serve as a handle, and (in dotted lines) the spur of a bolt or catch. Fig. 3 is a detail view of one of the trays with cylindrical cavities to contain eggs. Fig. 4 is a 100

detail view of the top of the bolt, showing a wire staple straddling the slot and serving to hold, or assist in holding, a strengthening-strip in position; also showing (in dotted lines) the position of the slot and the bolt in the slot. Fig. 5 is a detail view of the bottom of the fastening device, showing the housing and (in dotted lines) a cleat. Fig. 6 is a detail sectional view of the shipping-case, taken through the fastening device, showing an end of the case provided with a strengthening-strip and having a slot; also showing the cover, the sliding bolt, the sheet-metal plate that retains it in position, and the cleat that protects this and keeps up the frictional contact between the bolt and metal plate, and also showing a substitute device for the holes in the end of the box to serve as a handle for carrying the case.

20 In the drawings a box or receptacle is represented as divided by a partition into two compartments for the reception of rectangular trays made of paper-board, which are provided with any number of pockets or egg-receptacles made of similar material, connected to each other and also to the tray, in the usual manner of forming this class of trays, after the eggs have been placed in the trays, as each tray is put in place a sheet of paper being placed over it to separate the trays.

25 The box has ends A, which project a short distance above its sides, and are provided with slots a , which serve as keepers for either a catch or a sliding bolt. The grain of the wood forming these ends runs in a vertical direction, and to strengthen the ends, particularly at the slots, the inner faces of the projecting portions have a horizontal groove, a' , into which is laid a strip, a^2 , extending from one side of the box to the other. This groove and strip are just above the slot a' , particularly to afford strength there, and generally to prevent the projecting portion of an end from being broken off. In order further to strengthen an end at the slot, 30 a wire staple is driven into the top of the end immediately over and laterally beyond the slot, straddling it.

35 B represents a removable cover, which is provided at one end with a sliding bolt, b , and at the other end with a stationary bolt or catch, b' .

40 It will be observed that the two bolts or the sliding bolt and the catch are counterparts of each other, each being a piece of metal having a foot and heel portion and a spur or projection at a right angle therefrom. The spur or projection on the piece of metal, when used as the sliding bolt, serves as a handle to move the bolt forward to lock the case, or backward to 45 unlock it. The bolt is held in operative position under the cover by a metal plate, b^2 , which serves as a housing, and is secured to the removable cover by nails, screws, or otherwise. This metal plate not only serves as a housing 50 for the sliding bolt and to fasten it to the cover, but also serves to retain it against slipping or sliding and hold it in an extended or retracted

position by friction, to increase the friction between the plate and the bolt when desired.

55 The stationary bolt or catch b' , as above remarked, is of the same form and size as the sliding bolt, but it is attached to the removable cover in a different manner from that employed in attaching the sliding bolt, its projection or spur fitting tight in a hole or well in the cover. Along the under side of the cover, and in such position as to underlie the catch and the bolt, or with one over the catch alone, are two cleats, b^3 . These cleats are attached to the cover by nails, brads, or screws, 60 and are recessed at about their centers to receive the bolt, with its housing and the catch. These cleats are therefore not merely for the purpose of strengthening the cover, but serve as a protection to the bolt and the catch, while 65 in the case of the catch it is a cleat alone that holds it firmly in place. In addition to serving as protecting and retaining means for the bolt and catch, the cleats subserve the further function of a tightening device. If the bolt 70 should become loose in its housing by wear in long and constant use, it may be rendered tight—that is, the frictional contact of the housing may be rendered closer—by a blow upon the cleat.

75 The slots in the end pieces that receive the bolts being similar, it makes no difference which end of the box is used for the sliding bolt. This is a great advantage over those shipping-cases in which the construction will 80 permit the cover to fit in only one way, as this case requires no care or attention in putting it together.

85 In the outer face of each end of the shipping-case I provide four finger holes or cavities, which subserve the purpose of handles; but instead of these I may employ a notch, as shown in Fig. 6.

90 Having thus fully described my invention, what I claim, and desire to secure by Letters Patent, is—

95 1. In a shipping-case the cover of which is provided at one end with a bolt and at the other with a catch, bolt and catch to take into suitable slots in the ends of the box portion of the case, the combination, with a cover having a hole or well, and with a bolt or catch having a spur projecting from its foot and entering the hole or well in the cover, of a cleat recessed and attached to the cover, as described, bolt or catch being covered by the cleat at the recess—that is, boxed thereby—and held in position, adjusted, and protected by the cleat, substantially as specified.

100 2. In a shipping-case, the combination, with a cover having retaining devices projecting from it laterally, of a box portion having ends projecting above the cover, such ends being slotted to receive the retaining devices of the cover, being grooved across the upper margins 105 of the slots, and having cross-pieces secured in the grooves to serve as strengthening strips, substantially as described.

110 3. A shipping-case cover having a hole at

each end, provided with pieces of metal consisting of a foot portion to serve as a retaining part, and a spur to enter a hole in the cover, each piece of metal capable of serving either as 5 a sliding bolt or a stationary catch, and one piece being the counterpart of the other, whereby either end of the cover may be placed and held at either end of the box, substantially as described.

10 4. The combination of the cover having a hole, the sliding bolt, the metal plate or housing, and the recessed cleat, substantially as specified.

5. A shipping-case the box portion of which

has projecting ends provided with slots, and 15 with grooves extending across the upper margins of the slots, said grooves being filled with cross-pieces, which serve as strengthening strips, and are held by staples which straddle the slots, and serve additionally to strengthen 20 the ends of the slots, as shown and described.

In testimony whereof I affix my signature in presence of two witnesses.

JAMES FRANCIS BARTLETT.
